Des. 185,650
Patented July 7, 1959

185,650

WATER FOUNTAIN FOR LIVESTOCK

Maynard K. Voorhees and Robert W. Voorhees,
Cedar Falls, Iowa

Application October 30, 1958, Serial No. 53,205

Term of patent 14 years

(Cl. D12—2)

Figure 1 is a perspective view of a water fountain for livestock showing our new design;

Figure 2 is a front elevational view of the fountain; and
Figure 3 is a side elevational view thereof.

We claim:

The ornamental design for a water fountain for live-
stock, as shown.
